UNITED STATES PATENT OFFICE.

ELMER W. KELLEY, OF ROCHESTER, NEW YORK.

TRAFFIC-SIGNALING SYSTEM.

1,132,186.

Specification of Letters Patent. Patented Mar. 16, 1915.

Application filed December 29, 1913. Serial No. 809,245.

To all whom it may concern:

Be it known that I, ELMER W. KELLEY, of Rochester, in the county of Monroe and State of New York, have invented a new and useful Traffic-Signaling System, which is fully set forth in the following specification and shown in the accompanying drawings.

The present invention relates to traffic signaling systems and an object of the same is to provide a system by which signals may be given along any street or streets of a city for the purpose of pointing out the route which is to be taken by the fire apparatus, ambulances or other vehicles requiring that the traffic be cleared or stilled during the passage of such vehicles.

To this and other ends, the invention consists in certain parts and combinations of parts all of which will be hereinafter described, the novel features being pointed out in the appended claims.

In the drawings: Figure 1 is a diagram of a system constructed in accordance with the present invention; and Fig. 2 is a detailed sectional view of the casing which incloses a switch at a signaling station.

According to this invention, there is arranged at a common point or central station such, for instance, as a central office of the fire alarm system, an apparatus through which signals may be selected from a number distributed over the city to point out the route of the fire apparatus to a fire or an ambulance or other similar vehicle. In the illustrated embodiment, the signals are in the form of bells 1, each arranged at a station, the stations being indicated at *a*, *b*, *c*, *d*. It is apparent that any form of an electrically operated or controlled signal apparatus suitable for the purpose may be used. From the common point or central office which is indicated at *X* leads a common return or conductor 2 to which each of the signaling devices 1 is connected. Preferably each street of the city is provided with a conductor 2 to which all signals 1 along such street are connected. At the central office, the conductor 2 is provided with a main switch 3 which in turn is connected to a source of electricity 4. From the signals 1, conductors 5 connect with the switches 6, each conductor 5 leading from one of the signals 1 and connecting with one of the switches 6 which have a common connection 7 with the opposite side of the electrical

source, the switches 6 being arranged on the switch board at the central station in proximity to the main switches 3, and in an order corresponding to the order of the signals 60 along the streets.

It is apparent that a circuit is formed from the electrical source 4 through the common conductor 7, one of the switches 6, conductor 5 and its switch 8 and the signaling device 1 and from the latter by way of the common return or conductor 2 to the source of the electric current. At each station, the switch 8 is preferably arranged so as to break the conductor 5 in order to stop 70 the action of the signaling device 1 at such station. Preferably the switch 8 is inclosed within a casing 9 as shown in Fig. 2, the casing in this instance having a hinged closure 10 which is connected by a link 11 to the 75 blade of the switch 8, the purpose being that when the closure 10 is closed the switch 8 would be closed and when the closure is opened, the switch will be opened.

Arranged in parallel with the circuit of 80 each signaling device is an indicating circuit formed by a conductor 12 which is so connected with its conductor 5 at the signaling station that, when the switch 8 is opened, the current through the indicator 85 circuit 12 will be broken. This indicator circuit is also connected to the conductor 2 in common with the other indicator circuits, the point of connection being such that when the switch 3 is opened the current 90 through the indicator circuits will be broken. At the central station *X*, each indicator circuit 12 is provided with an indicating device such, for instance, as a lamp 13, the operation of which will be herein- 95 after described.

The operation of the invention is as follows: Assume that the circuits illustrated in the drawings represent the signals along one street of a city, the signals being located 100 about two or four blocks apart or at such a distance that one of the signals will be audible at any point along the street. When an alarm is sent in by way of the fire alarm system, which is preferably entirely separate from the present system, the operator at the central office, which is preferably also the central office of the fire alarm system, first closes the main switch 3, the switches 8 being under normal conditions also closed. The operator, assuming that a fire alarm box in proximity to the

signal d has been operated, closes all of the switches a' , b' , c' and d' either at once or successively at intervals sufficiently to have them operate in advance of the fire apparatus, provided it is possible to determine the position of the apparatus by calculating the time necessary to travel the different distances. This causes the signals a' , b' , c' , d' to give alarms, thus permitting the street to be cleared in advance of the fire apparatus. At the same time, the indicating lamps a^2 , b^2 , c^2 , and d^2 will light up, thus indicating to the central operator that their respective signals are in operation. When the fire apparatus reaches the station d , someone is sent to open the switch 8 at such station, which causes the indicating lamp d^2 to be extinguished, and the alarm at the station d to cease. When the lamp d^2 goes out, the operator at the central station immediately opens all of the switches 6 and the main switch 3, thus causing all of the remaining alarms to cease. Of course, the operator, by determining the position of the fire apparatus, can cut out any number of alarms in rear of the fire apparatus without waiting for the signal from the station at the destination of the fire apparatus.

While the entire system of the city might have a common return wire such as 2 herein before described, it is believed to be desirable to have one of such wires for each street with the signaling stations along such street connected thereto. It is desirable that the switch board at the central station should have the switches arranged in groups corresponding as near as possible to the arrangement of the streets of the city so that the operator may quickly select a route from any fire house to any alarm box. It is apparent that with this invention, the streets may be cleared in advance of the fire apparatus, thus shortening the time required for the apparatus to reach the fire and at the same time eliminating all accidents due to the collision of the apparatus with other vehicles or with pedestrians. It is apparent also that the same system may be employed for clearing the way in advance of ambulances or other vehicles which are required to make excessive speed in large cities.

What I claim as my invention and desire to secure by Letters Patent is:

55 1. A traffic signaling system comprising a plurality of signals distributed in the streets of a city, the distance between the signals being such that one of them will be effective as a signal at any point between any two proximate signals, and means for operating the signals to point out a path for fire apparatus, or the like.

2. A traffic signaling system comprising a plurality of audible signals distributed in the streets of a city, the distance between

any two proximate signals being such that one of them will be audible at any point between them, and means for selecting and operating any number of the signals to point out a path for fire apparatus or the like. 70

3. A traffic signaling system comprising a plurality of audible signals distributed in the streets of the city to point out a path for fire apparatus or the like, the distance between any two proximate signals being such that one of them will be audible at any point between them, separate circuits leading to each signal from a common point, and a plurality of switches arranged at such common point and each adapted to open and close one of the circuits. 75

4. A traffic signaling system comprising a plurality of audible signals distributed in the streets of the city to point out a path for fire apparatus or the like, the distance between any two proximate signals being such that one of them will be audible at any point between them, separate circuits leading from a common point to each signal, switches at such common point, each adapted 80 to control one of the circuits, and a switch at each signal for controlling the circuit of such signal at that point. 85

5. A traffic signaling system comprising a plurality of audible signals distributed in the streets of the city to point out a path for fire apparatus or the like, the distance between any two proximate signals being such that one of them will be audible at any point between them, separate circuits leading from a common point to each signal, switches at such common point, each adapted to control one of the circuits, and a switch at each signal for controlling the circuit of such signal at that point, and indicating circuits having indicators at the central point, each of said indicating circuits being controlled by the switch at one of the signals and the switch of the corresponding signal circuit at a common point. 95 100 105 110

6. A traffic signaling system comprising a plurality of audible signals distributed in the streets of the city to point out a path for fire apparatus or the like, the distance between any two proximate signals being such that one of them will be audible at any point between them, separate circuits including said signals and leading from a common point, said circuits having a common source of energy and having a common return wire, 115 a switch in said return wire by which all of said signals may be controlled simultaneously, and switches at the common point each adapted to control one of the signal circuits, said switches being arranged in the order of the arrangement of the signals. 120 125

7. A traffic signaling system comprising a plurality of audible signals distributed along a street of a city to point out a path for fire apparatus or the like, separate cir- 130

cuits including said signals and leading from a common point, and switches at such common point for controlling said circuit, said switches being arranged in the order of 5 the signals.

8. A traffic signaling system comprising a plurality of audible signals distributed along a street of a city to point out a path for fire apparatus or the like, separate circuits including said signals and leading from a common point, said circuits having a common return wire and a common source of energy, a switch in said return wire by which all of said signals may be controlled 10 simultaneously, switches at the common point each adapted to control one of the signals, switches at the signals each adapted to control one of the signals, and indicating 15 circuits connected to the common return wire and each controlled by the switch at 20

one of the signals, and one of the switches at the common point.

9. A traffic signaling system comprising a plurality of signals distributed along a street of a city, separate circuits including 25 said signals and leading from a common point, said circuits having a common return wire, indicating circuits having indicating devices therein located at the common point and in parallel with the signals, 30 switches at the signals each adapted to open and close one of the signal circuits and one of the indicating circuits, and means at the common point for opening and closing any one of the signal circuits.
